UNITED STATES PATENT OFFICE

1,988,624

BLOOD TRANSFUSION DEVICE

Ralph P. Kipp, Ossining, N. Y.

Application August 8, 1933; Serial No. 684,264

6 Claims. (Cl. 128—214)

The present invention relates to surgical devices, and more particularly to surgical devices used in the transfusion of blood, an important object of the invention being to provide a device of this character that will transfer blood from the donor to the patient, in a manner simulating the pumping action of the heart, with a straight short flow, eliminating the use of internal valves, limiting the amount of suction and with pressure under exact control, the device being readily and easily operated.

A further object of the invention is to provide a device of this character which will reduce the tendency of coagulation of the blood during the transfusion operation, due to the elimination of metallic valves or apparatus with which the blood contacts.

Another object of the invention is to provide a device which will avoid destructive friction upon the blood corpuscles and provide a device that is mechanically closed to the infiltration of air into the blood stream and one that has a nonreversing flow.

A still further object of the invention is to provide a device of this character which will accurately measure the blood transferred and provide for the observation of the flow of blood.

Another important object of the invention is the provision of a transfusion device wherein the parts in blood contact are few, the device being readily and easily dismantled to facilitate sterilization or replacement.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a transfusion device constructed in accordance with the invention.

Figure 2 is a plan view thereof.

Figure 3 is a sectional view taken on line 3—3 of Figure 1.

Figure 4 is a sectional view taken on line 4—4 of Figure 1.

Figure 5 is a sectional view taken on line 5—5 of Figure 1.

Figure 6 is a sectional view taken on line 6—6 of Figure 2.

Referring to the drawings in detail, the base of the machine is indicated generally by the reference character 5, and comprises a length of sheet metal material having downwardly extended end portions that support the base 5, in

spaced relation with the surface on which the device is positioned.

Tubular guides 6 extend downwardly from the base 5, and provide supports for the rods 7, that extend downwardly from the plate 8 which engages the elastic vessel or bulb 9, to compress the same. Lateral extensions 10 are formed on the tubular guides 6, and are disposed near the lower ends thereof, the lateral extensions providing supports for the levers 11 and 12 respectively, which are pivotally connected to the lateral extensions.

Depending from the base 5, are flanges 13 which are formed with bearings in which the shaft 14 of the crank arm 15, is mounted.

Secured to the inner end of the shaft 14, is a crank 16 which is provided with a crank pin 17 that is positioned within an opening formed in the lower end of the connecting arm 18, which connecting arm has pivotal connection with the plate 8, at 19. Secured to the plate 8, is a plate 20 that is provided with an extension 21 extending forwardly therefrom, the extension being disposed beyond the forward end of the plate 8, as clearly shown by Figure 2 of the drawings.

This plate 20 has pivotal connection with the plate 8, and is adapted to move vertically with respect to the plate 8, the plate 20 moving with the elastic vessel or bulb 9.

Thus it will be seen that when the elastic vessel or bulb 9 is in a compressed condition, the extension 21 will lie in the path of travel of the flange 22 of the crank arm 15, preventing further movement of the crank arm 15, to operate the elastic vessel or bulb 9, until the elastic vessel or bulb 9 has become filled, and the side walls thereof have expanded to the limits of their outward movements.

It will of course be understood that the operation of the elastic vessel or bulb 9 is controlled by the movement of the shaft 14 and crank arm 15, the construction of the mechanism being such that the elastic vessel or bulb 9 will be almost completely compressed and afterward expanded against the upper plates 20 and 8, during each rotation of the shaft 14 and crank arm 15.

Forming a part of the elastic vessel or bulb 9, is an elastic tube 23 which leads to the source of fluid supply, while at the opposite end of the vessel 9, is an elastic tube 24 that forms a part of the tube leading to the patient.

The valves that control the passage of fluid to and from the elastic vessel or bulb 9, play an important part in the operation of the device forming the subject matter of this invention, because these valves are so constructed that the blood or fluid is not in any way affected by the valves, and because these valves operate exteriorly of the tubes, the fluid pass-

ing through the device during transfusion, has no contact with the valves, thereby insuring against coagulation of the blood or fluid, during transfusion.

5 It will also be seen that the device is mechanically closed to the infiltration of air into the blood stream, and the blood stream has a nonreversing flow. Each of these valves includes a rod 25 that extends through an opening in the base 5, the upper end 26 of each rod being extended at right angles to overlie a portion of the tube, with which the valve is used.

10 A collar 27 is secured to each rod 25, adjacent to the lower end thereof, which collar provides 15 a support for the lower end of the coiled spring 28, associated therewith, the upper end of the coiled spring engaging the lower end of the bearing 29, through which the rod 25 extends.

15 Thus it will be seen that due to this construction, these valves are normally urged to their active positions, by means of the coiled springs 28.

20 As clearly shown by Figure 4 of the drawings, the lower end of the rod 25 of one valve, is engaged by the lever 11, while the lower end of the rod 25 of the opposite valve, is engaged by the lever 12.

25 The inner ends of the levers 11 and 12 are disposed in spaced relation with each other, and are so arranged that they will be engaged by the cams 29' and 30 respectively, which cams are secured to the shaft 14. These cams 29 and 30 are so arranged that when one cam is moving to elevate a valve, the other cam is moving away from the valve lever associated therewith, allowing the valve to move to compress the tube, cutting off the flow of liquid through the tube and elastic vessel or bulb 9.

30 The free end of the right angled portion 26 of each valve, is bifurcated to accommodate the latch 31 which swings upwardly to a position as shown by Figure 4, preventing the tube supported thereunder, from moving laterally to an inoperative position.

35 45 A coiled spring indicated by the reference character 32 acts to normally hold the latch member 31 against accidental displacement.

40 Connected with the tube 24, is a transparent tube 33, which embodies a lateral extension 34 to which the tube 35 is connected, the tube 35 leading from a suitable source of supply of saline or other fluid used during the transfusion operation. Tube 36 leads to the patient, and connects with one end of the tube 33, as shown by figure 1.

45 55 In the operation of the device, the tube 23 leading from the donor, is open, and the operator moves the crank arm 15 rotating the shaft 14. As the shaft 14 rotates, the plate 8 moves downwardly compressing the elastic vessel or bulb 9. After the bulb has been compressed further rotation of the shaft will cause the valve associated with the tube 23, to open, allowing fluid or blood to be drawn into the elastic vessel or bulb 9.

60 65 70 As the shaft is further rotated, the valve associated with tube 23 will close, and the valve associated with tube 24 will open to the end that when the plate 8 moves downwardly, the blood or fluid drawn into the elastic vessel or bulb 9, will be forced through the tube 36, to the patient.

75 In view of the fact that the capacity of the elastic vessel or bulb 9 is known, the quantity

of fluid or blood used in the transfusion operation may be readily determined.

80 In the event that the elastic vessel or bulb 9 does not expand to its fullest extent the extension 21 will engage the flange 22, restricting further movement of the crank arm 15, until the elastic vessel or bulb 9 has fully expanded.

85 I have thus described the invention.

I claim:

90 1. A transfusion device comprising a base, a pump embodying an elastic bulb, mounted on the base, a pump operating means comprising a plate, a plate pivotally connected with the first mentioned plate and contacting the bulb, the pivoted plate adapted to move with the bulb 15 as the bulb is being distended, a lever adapted to move the plates, compressing the bulb, and means on the pivoted plate and adapted to engage the lever, restricting movement of the lever until the bulb has been completely distended. 20

95 2. A transfusion device comprising a base, an elastic pump in the form of a bulb, mounted on the base, a vertically movable plate, above the bulb and adapted to compress the bulb, forcing material from the bulb, valves adapted to compress the ends of the bulb, controlling the passage of liquid to and from the bulb, means for operating the vertically movable plate and means controlled by the plate operating means for operating the valves simultaneously with the 30 operation of the vertically movable plate.

100 3. A transmission device comprising a base, an elastic pump in the form of an elongated bulb, the ends of the bulb being reduced, providing inlet and outlet tubes, an operating plate adapted to compress the bulb against the base, forcing material from the bulb, and valves adapted to clamp the reduced ends of the bulb for controlling the passage of material to and from the bulb.

105 4. A transfusion device comprising a base, a pump in the form of an elongated bulb, positioned on the base, a movable plate engaging the bulb, means for operating the movable plate to compress the bulb against the base, forcing liquid from the bulb, clamping members clamping the ends of the bulb and controlling the passage of liquid to and from the bulb, and means controlled by the action of the operating means for operating the clamping members.

110 5. A transfusion device comprising a base, a pump in the form of a bulb, positioned on the base, clamping members clamping the ends of the bulb, means for compressing the bulb, pivoted members engaging the clamping members 55 and adapted to urge the clamping members to their inactive positions when the bulb compressing means is actuated.

115 6. A transfusion device comprising a base, an elastic pump in the form of a compressible bulb, 60 mounted on the base, a compressing plate mounted above the bulb, a pivoted plate mounted on the compressing plate, said pivoted plate resting on the bulb and adapted to compress the bulb when the compressing plate moves downwardly, operating means for operating the compressing plate, said operating means including a handle, and means on the pivoted plate and lying in the path of travel of the handle, for restricting movement of the handle until the 70 bulb has been entirely distended, and valves controlling the flow of liquid through the bulb.
